(57) **CLAIM**

The ornamental design for a foldable multipurpose cushioned water-resistant mat as shown and described.

DESCRIPTION

FIG. 1 is a perspective view showing of the foldable multipurpose cushioned water-resistant mat of Applicant's new design in an open position.

FIG. 2 is a top plan view of the foldable multipurpose cushioned water-resistant mat of FIG. 1.

FIG. 3 is a left side elevation view of the foldable multipurpose cushioned water-resistant mat of FIG. 1.

FIG. 4 is a right side elevation view of the foldable multipurpose cushioned water-resistant mat of FIG. 1.

FIG. 5 is a front elevation view of the foldable multipurpose cushioned water-resistant mat of FIG. 1.

FIG. 6 is a rear elevation view of the foldable multipurpose cushioned water-resistant mat of FIG. 1.

FIG. 7 is a bottom plan view of the foldable multipurpose cushioned water-resistant mat of FIG. 1.

FIG. 8 is a perspective view showing of the foldable multipurpose cushioned water-resistant mat of FIG. 1 in a partial widthwise folded position.

FIG. 9 is a perspective view showing of the foldable multipurpose cushioned water-resistant mat of FIG. 1 in a widthwise folded position.

FIG. 10 is a top plan view of the foldable multipurpose cushioned water-resistant mat of FIG. 9.

FIG. 11 is a left side elevation view of the foldable multipurpose cushioned water-resistant mat of FIG. 9.

FIG. 12 is a right side elevation view of the foldable multipurpose cushioned water-resistant mat of FIG. 9.

FIG. 13 is a bottom plan view of the foldable multipurpose cushioned water-resistant mat of FIG. 9.

FIG. 14 is a front elevation view of the foldable multipurpose cushioned water-resistant mat of FIG. 9.

FIG. 15 is a rear elevation view of the foldable multipurpose cushioned water-resistant mat of FIG. 9.

FIG. 16 is a perspective view showing of the foldable multipurpose cushioned water-resistant mat of FIG. 9 in a partial lengthwise folded position.

FIG. 17 is a top perspective view showing of the foldable multipurpose cushioned water-resistant mat of FIG. 9 in a lengthwise folded position.

FIG. 18 is a bottom perspective view showing of the foldable multipurpose cushioned water-resistant mat of FIG. 9 in a lengthwise folded position.

FIG. 19 is a top plan view of the foldable multipurpose cushioned water-resistant mat of FIG. 17.

FIG. 20 is a left side elevation view of the foldable multipurpose cushioned water-resistant mat of FIG. 17.

FIG. 21 is a right side elevation view of the foldable multipurpose cushioned water-resistant mat of FIG. 17.

(Continued)

FIG. 22 is a bottom plan view of the foldable multipurpose cushioned water-resistant mat of FIG. 17.

FIG. 23 is a front elevation view of the foldable multipurpose cushioned water-resistant mat of FIG. 17; and, FIG. 24 is a rear elevation view of the foldable multipurpose cushioned water-resistant mat of FIG. 17.
